UNITED STATES PATENT OFFICE.

ARTHUR J. BRIGGS, OF SYRACUSE, NEW YORK, ASSIGNOR TO THE SMITH PREMIER TYPEWRITER COMPANY, OF SYRACUSE, NEW YORK, A CORPORATION OF NEW YORK.

TYPE-WRITING MACHINE.

No. 863,052.

Specification of Letters Patent.

Patented Oct. 22, 1907.

Application filed April 7, 1906. Serial No. 310,440.

To all whom it may concern:

Be it known that I, ARTHUR J. BRIGGS, a citizen of the United States, and a resident of Syracuse, in the county of Onondaga and State of New York, have invented certain new and useful Improvements in Type-Writing Machines, of which the following is a specification.

My invention relates to typewriting machines and especially to an indicator device to be used in connection with a polychrome ink ribbon or an ink ribbon having fields of different characteristics.

My invention consists in certain features of construction and combinations and arrangements of parts all of which will be fully set forth hereinafter and particularly pointed out in the claims.

In the accompanying drawings, Figure 1 is a right-hand side elevation, with parts in section, of a typewriting machine having my invention embodied therein. Fig. 2 is a detail fragmentary front view of certain 20 of the devices embodying my invention. Fig. 3 is a view in section of a stop device employed in the machine, the section being taken substantially on the line $z-z$ of Fig. 2 and looking in the direction of the arrow $z-z$ said line. Fig. 4 is a top plan view of the machine with the carriage, carriage rails and other parts of the machine removed. Fig. 5 is a detail plan view showing an indicator card detached from the machine. This view is on a larger scale than Fig. 4.

My invention is applicable to typewriting machines 30 generally but in the present instance I have shown it applied to a Smith Premier typewriter. The main frame of this machine comprises a base portion 1, posts 2 and a top plate 3 supported by said posts. Rails 4 mounted on said top plate support a carriage 5 by anti-friction ball or roller bearings and a platen 6 is mounted on said carriage. Said carriage is provided with a feed rack 7 meshing with a pinion 8 that is connected with an escapement wheel covered up by a housing 9. Feed dogs 10 co-operate with said escapement wheel, 40 said feed dogs being mounted on the upper end of a vertical rock shaft 11 journaled in the top plate 3 and in the base 1. An arm 12 projecting from said rock shaft has its free end in a slot in an arm 13 mounted on a reciprocating universal bar or gate 14 that is operated by arms projecting from rock shafts 15 that are journaled in the base of the machine and are operatively connected with printing keys 16, restoring springs 16^a operating to restore the rock shafts and the parts connected therewith to normal position. Each 45 of the rock shafts 15 has an arm that is connected by a link 17 with one of a series of type bars 18 each of which at its free end carries a type 19 adapted to strike against the under face of the platen 6. The mechanism thus briefly described is the well known mechan-

ism of the Smith Premier typewriting machine, although, as far as my invention is concerned it may be of any suitable construction.

On each side of the machine a ribbon spool shaft 20 is journaled in the posts 2 and ribbon spools 21 and 22 are mounted on said shafts, one of said ribbon spools 60 being mounted on its shaft back of the printing line and the other of said spools being mounted forward of the printing line. In the present instance the right-hand ribbon spool 21 is back of the printing line and the left-hand spool 22 is forward of the printing line. 65 These ribbon spools are situated below the top plate and the ribbon is lead from each of them up to the top plate and over a plate 23 secured to the top plate and under a plate 24. The ribbon is divided into three longitudinally extending fields a , b and c is guided 70 from one of the spools to the other in an off-set path, the off-set portion of which is beneath the printing point. To this end a guide plate 25 is mounted in the machine in such a fashion that it is adapted to be slid to the right or left. The middle portion of said guide 75 plate is cut out to form a central opening 25^a and wires 26 and 27 are secured at their ends to the inner edges of the plate 25 which surround the opening 25^a, each of said wires extending across the central opening in said plate at an angle of substantially 45° to a line parallel 80 to the direction of travel of the carriage. The ribbon passes upwardly and inwardly from the spool 21 to the right-hand plate 23 and thence under the associated plate 24 beneath the plate 25 to the wire 26. The ribbon then passes up over the wire 26, thence straight 85 towards the front of the machine, over the wire 27 and down and beneath the plate 25 and straight across the machine under the left-hand plate 24 and downwardly and outwardly from the outer edge of the left-hand plate 23 to the spool 22, as will be clearly understood 90 by reference to Fig. 4. The types are adapted to strike the ribbon through the central opening 25^a in the guide plate and forward of the spool 21 and back of the spool 22.

The printing point is indicated by the reference character z when the parts are disposed as shown in Fig. 4. The types strike the part of the ribbon that extends in a front to back direction between the wires 25 and 26. The carriage is driven by a spring drum 28 and the ribbon spools are connected up to said spring drum in any suitable manner to impart an automatic longitudinal feed to the ribbon. Each of the shafts 20 also carries a crank handle 20^a, by which the ribbon may be fed manually. It will be perceived that with the guide plate 25 in the position shown in Fig. 4 the types will 100 strike the ribbon at z near the left-hand edge of the fore and aft extending portion thereof and as the ribbon is fed longitudinally the type will strike along the lon-

itudinal line or field *a* of the ribbon near this edge. This is the edge of the ribbon that is nearest the front of the machine when the ribbon is wound on the spools. It will also be perceived that if the plate 25 be moved 5 toward the left the types will strike a portion of the ribbon nearer the middle thereof or within the field *b* and if it be moved still further toward the left they will strike near the right-hand edge of the ribbon within the field *c*, that is to say, at the edge which, on the 10 spools, is nearest the back of the machine. In order that the plate 25 may be adapted to be moved to one or another of these several positions, said plate is slidably mounted on rails 29 and 30 which are secured by screws 31 to the top plate of the machine. By an inspection of Fig. 4 it will be seen that this plate 25 lies beneath the carriage rails 4 which prevent it from being lifted off of the rails or tracks 29 and 30.

At its forward edge the plate 25 is formed with arms 32 which are bent down over the front and rear edges 20 of the forward rail 30 so as to prevent the guide plate 25 from turning in a horizontal plane. A spring arm 33 projecting toward the front of the machine from the plate 25 has a finger piece 34 mounted thereon and it is by manipulation of this finger piece that the plate 25 25 may be slid back and forth to its several positions. The arm 33 projects out from under the carriage rail 4 and extends far enough toward the front of the machine to be free of all the carriage devices and to be in a position where it may be readily reached by the hand of 30 the operator. Said arm 33 passes beneath a bar 35 that extends transversely of the machine and is secured to the top plate by screws 36. The bar 35 is formed on its under side with notches 37 (Fig. 2) and a tooth 38 (Figs. 4 and 4) is struck up from the arm 33 into position 35 to enter these notches, which it does by reason of the resilience of said arm 33. This tooth coöperating with the notches 37 serves to hold the plate 25 in any one of the several positions to which it may be adjusted by the operator. The extreme right hand position to 40 which the plate 25 can be moved is determined by a post 39 which supports the bar 35 and which also serves as a stop for the arm 33. The bar 35 is also provided with a left-hand post 39 which is set so far to the left of the right-hand post that the plate 25 may be moved so 45 far to the left that the guide plate 25 and that portion of the ribbon contained within the central opening therein are entirely at the left-hand side of the printing point. It is this position of the guide plate 25 that makes it possible to do mimeograph work on the machine and also enables the operator to insert the handle 50 for the type cleaning brush that is commonly used in the Smith Premier machine.

In order to normally prevent the operator from carelessly moving the ribbon guide so far to the left as to 55 move the ribbon entirely away from the printing point, or to prevent him from moving it to such a position that the type might strike the plate 25 itself, an adjustable stop 40 is mounted on the bar 35. Said stop consists of a plate of sheet metal bent up into the form 60 shown in Figs. 2 and 3. This piece of metal extends across beneath the bar 35 and is bent up in front of said bar as shown in Fig. 3 and also back of said bar, the rear upward extension of it being bent forward to form a finger piece 41. The stop is normally pressed upward 65 against the under surface of the bar 35 by a U-shaped

flat spring 42 that is slipped over the bar and under the stop 40 from in front and the two arms of which tend to spring together. The stop 40 has a tooth 43 struck up therefrom in such position that when the stop is in its normal position said tooth enters one of the notches 70 37 and thus prevents motion of the stop longitudinally of the bar 35. By pressing down on the finger piece 41, the stop may be depressed to the position shown in dotted lines in Fig. 3, in which position the tooth 43 is out of engagement with the notch 37 so that the stop 75 may be slid along the bar 35. Ordinarily this stop will stand in some such position as that shown in Fig. 2 where it will prevent the operator from carelessly moving the guide plate 25 too far to the left, but in case it is desired to move the ribbon entirely away from the 80 printing point the stop may first be slid to the left and then the guide plate may also be slid to the left. The stop 40 has depending therefrom a tooth 44 to more perfectly close the opening between the bar 35 and the top plate.

It will be perceived that the ribbon mechanism described is adapted to be used either with a ribbon of one solid color or with a polychrome ribbon. It will also be perceived that a ribbon may be put into this mechanism having longitudinal fields of different characteristics and that these fields may be distributed over the ribbon in any desired manner. The ribbon may have either two or more longitudinal stripes of different characteristics and these stripes may be of any suitable width so long as each stripe is wide 90 enough for the types to strike it withoutlapping over on to another stripe. In the present instance I have shown a three-color ribbon, having a front stripe *a* of red copying ribbon, a middle stripe *b* of purple copying ribbon and a rear stripe *c* of black record ribbon. 100 In this instance also I have shown the red and black stripes as comparatively narrow and the purple stripe as much wider than the other stripes, for the reason that this ribbon is designed for use by persons who will probably use the purple copying ribbon more 105 than either of the others.

The ribbon mechanism thus far described is not of my invention but is the invention of Alexander T. Brown. For use in connection with this ribbon mechanism I have provided a detachable indicator card, plate or equivalent device 45 adapted to coöperate with a pointer 46 formed on the forward end of the arm 33. In order to mount this indicator card detachably on the machine a plate 47 is secured at its forward edge to the top plate 3 by screws 48, the rear edge of said plate lying beneath the posts 39 of the bar 35 and being secured in place at these points by the screws 36. The part of the plate 47 that lies just in front of the pointer 46 is cut away to form a sight opening 49 having a length transversely of the machine substantially equal to the width of the ink ribbon. The part of the plate 47 that immediately surrounds this sight opening is stamped up so as to leave between this part of the plate 47 and the top plate 3 a space sufficient for the indicator card 45. This raised portion of the plate 47 extends to the forward edge of said plate so as to leave an opening 49* (Fig. 2) through which the card 45 can be slipped into position beneath the plate 47 from the front. The indicator card or plate may be made of any suitable material and it has that portion of its up- 115 120 125 130

per surface that lies beneath the sight opening 49 colored with colors corresponding to those of the ink ribbon. The present card has a field *a'* of red, a field *b'* of purple and a field *c'* of black, the widths of these 5 several fields being equal to the widths of the corresponding fields in the ink ribbon. The colors on the card show the colors of the corresponding parts of the ribbon and in addition to this, characters may be printed on the card if desired to show the sort of ink 10 on the different fields of the ribbon. For example, the letter R may be printed on the black field *c'* to indicate that this part of the ribbon is record ribbon and the letter C may be printed on the purple and red fields to indicate that these portions of the ribbon are 15 copying ribbon or the wide purple field may have the word "copy" printed thereon as shown in Fig. 5. The card is made readily detachable so that in case another ribbon is used and inked in some different way, a corresponding card may be inserted in the card 20 holder. For example, the black stripe might be made wider and the purple stripe narrower in some other ribbon, in which case the card would be modified correspondingly; or another ribbon might be used having only two fields instead of three and a card divided in 25 the same way would be put into the machine at the same time that the ribbon was.

This invention contemplates the manufacture of different styles of ribbon having different colors and different numbers of colors suitable for the use of different 30 classes of customers, and it is contemplated that in each package of ribbon sold there shall be placed an indicator card corresponding to that particular ribbon. For example, if the customer had been using his machine equipped in the manner shown in the drawings and 35 decided that he required a two-color ribbon, one stripe being black record ribbon and the other purple copying ribbon, when he purchased this new ribbon he would find in the same package with the ribbon an indicator card adapted to be inserted in the machine, which 40 card would correspond in its indications to the colors on the new ribbon. The use of a detachable indicator card in the manner above described adds greatly to the convenience of a polychrome ribbon mechanism. As these polychrome ribbon mechanisms have been 45 constructed and used heretofore, each machine has been adapted for only one style of polychrome ribbon; but by the use of the present device a manufacturer may produce as many styles of polychrome ribbon as the market demands, so that any user of the typewrit- 50 ing machine may purchase any style of ribbon that he chooses, or may, if he chooses, have several different styles of ribbon and he may at any time insert in his machine any one of these ribbons and insert the corresponding indicator card, when his machine will be 55 fully equipped for the use of that particular ribbon in the most convenient manner.

The term "indicator card" employed herein is used in a broad sense and is intended to apply to any indicator card, plate or equivalent indicating device 60 whether it be in the nature of a piece of the ribbon itself or any suitable means corresponding in function to the card 45.

Various changes may be made in the details of construction and arrangement without departing from my 65 invention.

What I claim as new and desire to secure by Letters Patent, is:—

1. In a typewriting machine and ribbon mechanism, the combination of printing instrumentalities; an ink ribbon divided into fields of different characteristics; hand controlled means for confining the co-operation of the printing instrumentalities therewith to any desired field; and means for indicating what particular field of the ribbon is in position to cooperate with the printing instrumentalities, said indicating means comprising an index, a 70 co-operating indicator card or plate divided into fields corresponding to the divisions of the fields of the ink ribbon, and means for removably securing the indicator card or plate in the operative position, whereby each ribbon may have and may be used in the machine in connection with 80 its own indicator card showing the peculiar characteristics of that ribbon.

2. In a typewriting machine and in a ribbon mechanism, the combination of a ribbon having fields of different characteristics; controlling means operable at will to bring either of said fields to the printing point; and an indicator for said controlling means comprising a pointer or index, an indicator card or plate marked to correspond with the different fields of the particular ink ribbon in use, and a card or plate holder for said indicator card or plate, said holder being adapted to permit the card or plate to be readily inserted and removed, whereby each ribbon may have and may be used in the machine in connection with its own indicator card showing the peculiar characteristics of that ribbon. 95

3. In a typewriting machine and ribbon mechanism, the combination of a ribbon having fields of different colors; controlling means operable at will to bring either of said fields to the printing point; and an indicator for said controlling means comprising a pointer or index, and 100 an indicator card or plate marked with colors corresponding to the colors on the ink ribbon, and a card or plate holder for said indicator card or plate, said holder being adapted to permit the card or plate to be readily inserted and removed, whereby each ribbon may have and may be used 105 in the machine in connection with its own indicator card showing the peculiar characteristics of that ribbon.

4. In a typewriting machine and in a ribbon mechanism, the combination of an ink ribbon having longitudinal fields of different colors or characteristics; a ribbon guide 110 adapted to be moved to bring any selected one of said fields to the printing point; an indicator card or plate marked with colors or characteristics corresponding to the colors or characteristics on the ink ribbon; a card or plate holder in which said card or plate may be readily secured and from which it may be readily removed; and a pointer co-operating with said indicator card or plate to show which of the fields of the ribbon is at the printing point, whereby each ribbon may have and may be used. 120 in the machine in connection with its own indicator card showing the peculiar characteristics of that ribbon.

5. In a typewriting machine and in a ribbon mechanism, the combination of a ribbon guide that is movable to bring any desired longitudinal field of an ink ribbon to the printing point so that said ribbon guide is adapted for 125 use with different ribbons each having longitudinal fields of different characteristics, even though the different ribbons employed may be differently divided; an ink ribbon adapted to be used in said ribbon guide and having longitudinal fields of different characteristics; an indicator card divided into fields corresponding to those of the particular ribbon in use; a card-holder in which said card is adapted to be readily mounted and from which it is adapted to be readily detached; and a pointer for co-operating with said detachable card to indicate which of the 130 fields of the ribbon is at the printing point, whereby each ribbon may have and may be used in the machine in connection with its own indicator card showing the peculiar characteristics of that ribbon. 135

6. In a typewriting machine and in a ribbon mechanism, the combination of a ribbon guide adapted to be moved to different positions to bring any one of a plurality of longitudinal fields of the ink ribbon to the printing point; means for controlling said guide so as to cause any selected 140 one of the fields of the ribbon to be brought to the print- 145

ing point; an ink ribbon adapted to be used in said ribbon guide and having longitudinal fields of different characteristics; an indicator card marked with fields corresponding to those of the particular ribbon recited; a card-holder 5 in which said card is adapted to be readily mounted and from which it may be readily removed; and a pointer co-operating with said indicator card and indicating which field of the ribbon the guide controlling means is set to bring to the printing point, whereby each ribbon may have 10 and may be used in the machine in connection with its own indicator card showing the peculiar characteristics of that ribbon.

7. In a typewriting machine and in a ribbon mechanism, the combination of type; means for guiding and controlling an ink ribbon; hand operated means adjustable to different positions to cause said type to strike said ink ribbon at different points transversely of said ribbon, so that, as said ribbon is fed longitudinally, different longitudinal fields of the ribbon will be used depending on the 15 different positions to which said hand operated means is adjusted; an ink ribbon adapted for use in said ribbon mechanism and having longitudinal fields of different characteristics; and an indicator device for said hand operated means, said indicator device comprising a pointer 20 and a card-holder and a card marked with different fields corresponding to those of the particular ribbon employed, said card-holder being adapted to have said card readily mounted therein and readily removable therefrom, whereby each ribbon may have and may be used in the machine in connection with its own indicator card showing the peculiar 25 characteristics of that ribbon.

8. In a typewriting machine and in a ribbon mechanism, the combination of a ribbon guide movable to different points to bring different longitudinal fields of the ribbon 30 to the printing point; an ink ribbon mounted in said ribbon guide and having longitudinal fields of different characteristics; a pointer connected with said ribbon guide and movable across the top plate of the machine; a card-holder comprising a plate mounted on the top plate 35

of the machine and having a sight opening therein and another opening; and an indicator card divided into fields corresponding to those of the ink ribbon and adapted to be inserted in the last mentioned opening and to be seen, when in position, through said sight opening and adapted to co-operate with said pointer to indicate which field of the ink ribbon is at the printing point, whereby each ribbon may have and may be used in the machine in connection with its own indicator card showing the peculiar characteristics of that ribbon. 40

9. In a typewriting machine and in a ribbon mechanism, the combination of means for guiding and controlling an ink ribbon; an ink ribbon having longitudinal fields of different characteristics; hand operated means movable to different positions to indicate which of the fields of the ribbon is at the printing point; a pointer on said hand operated means; and an indicator card divided into fields corresponding to those of the ribbon, the several fields of the card being colored to correspond with the colors of the different fields of the ribbon and each field of the card being marked with a character to indicate some other characteristic of the corresponding field of the ribbon, such as record ribbon or copying ribbon, whereby each ribbon may have and may be used in the machine in connection with its own indicator card showing the peculiar characteristics of that ribbon. 50

10. An inking ribbon divided into fields of different characteristics, and an indicator card correspondingly divided and having means to designate the characteristics of the several fields of the inking ribbon, both said ribbon and card being adapted to be mounted on a typewriting 55 machine.

Signed at Syracuse, in the county of Onondaga, and State of New York, this 5th day of April A. D. 1906.
